UNITED STATES PATENT OFFICE

CHARLES W. GOFF, OF ST. JOSEPH, MISSOURI.

SHINGLING-BRACKET.

1,159,372.

Specification of Letters Patent.

Patented Nov. 9, 1915.

Application filed October 16, 1912, Serial No. 726,145. Renewed September 30, 1915. Serial No. 53428

To all whom it may concern:

Be it known that I, CHARLES W. GOFF, a citizen of the United States, residing at St. Joseph, in the county of Buchanan and State of Missouri, have invented new and useful Improvements in Shingling-Brackets, of which the following is a specification.

This invention is an improved bracket especially adapted for use in shingling roofs and for fastening stage hooks, holding ladders and to serve as shelves for supporting paint pots, tinners' fire pots and the like, the object of the invention being to provide an improved bracket of this character which may be adjusted for use on a roof of any pitch and which when not in use may be compactly folded so as to occupy but little space, the invention consisting in the construction, combination and arrangement of devices hereinafter described and claimed.

In the accompanying drawing:—Figure 1 is a perspective view of a shingling bracket constructed in accordance with my invention, showing the same in set up position ready for use. Fig. 2 is a longitudinal sectional view of the same in folded position.

My improved shingling bracket comprises a main member 1 to bear on the roof, a standard member 2 hinged at its lower end 30 to the lower end of the main member and a supporting member 3 hinged to the main member and adapted to be adjustably connected to the standard member. The members of my improved shingling bracket are 35 each made of suitable sheet metal and the standard member 2 is formed at its lower end with spurs 4 which are adapted to be driven into the roof to support the bracket thereon and prevent the bracket from slipping, the main member 1 bearing on the inclined upper surface of the roof. The standard member is provided with a curved opening or slot 5 and is also provided near opposite sides with series of adjusting slots 6.

45 The supporting member 3 has an opening
7 to receive a stage hook the bottom of a
paint pot, fire pot, or the like and is also
provided at its lower free end with a pair
of hooks 8 which may be engaged with any
50 of the adjusting slots 6 in order to secure
the supporting member to the standard
member and at any required angle with rela-
tion to the main member 1, according to the
angle of the roof on which the device is em-

ployed. This adjustable connection between the standard member and the supporting member enables the bracket to be employed on roofs of any pitch. 55

On the upper side of the main member at a point between the hinge connections of the standard member and supporting member is a reinforcing plate 9 the lower or outer end of which is rounded and upturned to provide a curved flange 10, which, when the bracket is in folded position, as shown in Fig. 2, passes through the curved slot 5. When the bracket is in folded position the standard member 2 bears directly against the upper side of the main member and the supporting member 3 bears directly against the upper side of the standard member.

It will be understood from the foregoing and by reference to the drawing that my improved shingling bracket is extremely simple, is very strong and durable and is adapted for a variety of uses and on roofs of any pitch. 75

The bracket may be made of any suitable size and, in practice, may be supplied with as many dogs as necessary, according to the size of the bracket. 80

While I have herein shown and described a preferred form of my invention, I would have it understood that changes may be made in the form, proportion and construction of the several parts without departing from the spirit of the invention and within the scope of the appended claim. 85

I claim:—

As a new article of manufacture, the herein described sheet metal shingling bracket comprising a main member to bear directly on a roof and having its lower end bent downwardly at a slight angle, a supporting member hinged at one end to the main member and having downturned hooks at its outer end and a standard member having its lower end bent downwardly at a slight angle and hinged to the lower end of the main member and provided also at its lower end with securing studs bent outwardly therefrom to project from the angle between the main member and standard and enter the roof when the bracket is set up, said standard member having adjusting openings for engagement by the hooks of the supporting member, the bent lower member affording space to clear the hooks of the supporting 100 105 110

member and adapt the device to be compactly folded when not in use and with the main member, the standard member and supporting member parallel, the hinge which connects the supporting member to the main member serving to space said members apart and to also reinforce the main member, the said standard member when the bracket is folded lying in the space formed by the said

hinge between the supporting member and 10 the main member.

In testimony whereof I affix my signature in presence of two witnesses.

CHARLES W. GOFF.
